UNITED STATES PATENT OFFICE.

ROWLAND MCWILLIAMS, OF NEW YORK, N. Y.

CONCRETE STRUCTURE.

Application filed August 19, 1920. Serial No. 404,639.

To all whom it may concern:

Be it known that I, ROWLAND MCWILLIAMS, a citizen of the United States, and a resident of the borough of Manhattan, city, county, and State of New York, have invented certain new and useful Improvements in Concrete Structures, of which the following is a specification.

My invention relates to concrete structures, and particularly to structures of reinforced concrete, and has for its object to provide improved means for keeping the parts of such structures at the proper distance from each other. When used in connection with blocks, the invention serves to preserve the alignment of adjacent blocks. Several ways of carrying out and employing the invention will now be described in detail with reference to the accompanying drawings, in which—

Fig. 1 is a partial plan view of a floor or ceiling embodying one form of my invention; Fig. 2 is a cross section on line 2—2 of Fig. 1; Fig. 3 is a plan showing part of a floor or ceiling with a second form of my invention; Fig. 4 is a vertical section on line 4—4 of Fig. 3; Fig. 5 is a partial perspective view showing the two members of a spacing device, before said members are assembled; Fig. 6 is a perspective view of the spacing device employed in the construction Figs. 3 and 4; Fig. 7 shows a beam embodying my invention, in section on line 7—7 of Fig. 8; Fig. 8 is a cross section of said beam on line 8—8 of Fig. 7; Fig. 9 is a horizontal section of a column embodying my invention, on line 9—9 of Fig. 10, the latter being a vertical section on line 10—10 of Fig. 9; and Fig. 11 is a partial horizontal section of a modification.

In each form of my invention illustrated herein, the improved spacing device comprises two members intersecting substantially in X-fashion and having their ends bent relatively to their main portions. These members may consist of bands of thin sheet metal (preferably iron), connected at their crossing points in any suitable manner, as by slitting each of the members A, B for half its width and then fitting them together as indicated best in Figs. 5, 6, and if desired the members may then be welded together at their intersections. The ends of the members are bent in accordance with the particular structure in which they are to be used.

Thus, in Figs. 1 and 2, each of the four ends C is bent in its full width in such a way that these ends will be parallel with each other, and those at adjacent ends of different members will lie in the same plane, all of the ends C extending outwardly, that is to say, the aligning ends extend in opposite directions from the respective members A, B, as shown in Figs. 1 and 2, the parallel ends C of these spacing devices engage blocks D of two adjacent parallel rows, thus keeping said rows at the proper distance from each other. The spacing devices also serve as supports or chairs for the reinforcing rods E which in this particular construction extend in one direction only, parallel to the rows of blocks D. It will be understood that when the structure is finished, the spacing devices as well as the reinforcing rods E are imbedded either partly or entirely in a body of concrete F.

In a two-way re-inforced construction, an example of which is shown in Figs. 3 and 4, the spacing devices are of the same character as described above, but their ends are slit lengthwise at a level midway between the top and the bottom (Fig. 6), thus forming eight end portions C' to C⁸ inclusive of half the height of the members A, B, the two upper portions C', C² and the two lower portions C³, C⁴ being parallel and occupying the same relation to each other (so far as their direction is concerned) as the ends C first described, while the aligning lower portions C⁵, C⁶ are parallel to the aligning upper portions C⁷, C⁸ are parallel to each other but at right angles to the portions C' to C⁴. Being bent in different directions, the portions C' to C⁸ form angular pockets at the four ends of the intersecting members A, B, and by bringing the walls of these pockets into engagement with the corners of blocks D' arranged in rows of two intersecting directions, as indicated in Figs. 3 and 4, I not only preserve the proper spacing between adjacent rows, but give each individual block its correct position. In this case also, the spacing device serves as a support or chair for the re-inforcing rods E', E² arranged between the blocks and imbedded in a body of concrete (not shown).

In Figs. 7 and 8, F' indicates the concrete body of a beam having parallel re-inforcing rods E³ located in its interior and imbedded in the concrete, together with chairs or spacing devices of the character shown in Fig.

1, but preferably in this case the ends C are made longer than in Fig. 1. These spacing devices hold the rods E³ in the proper initial position.

5 In Figs. 9 and 10 spacing devices of the character described with reference to Figs. 3, 4 and 6 are shown within a column of concrete F'' reinforced by vertical rods E⁴ (round or square) extending within the 10 pockets at the ends of the intersecting members A, B. The rods may be welded to the spacing devices, which also act as ties. Fig. 9 shows the bent ends of the spacing devices in alignment with one another, in 15 substantially the same manner in which the end C⁵ of Fig. 6 aligns with the end C⁶, and the end C⁷ of said Fig. 6 with the end C⁸. As indicated in Fig. 11, the ends of the spacing members may be bent around the 20 rods E⁴ if desired.

While I have disclosed my invention in its special application to horizontal elements, such as floors, ceilings or beams and to columns, it will be understood that the 25 position in which the structure is used is immaterial to my invention. Various modifications may be made without departing from the nature of my invention as set forth in the appended claims.

30 I claim as my invention:

1. A reinforcing structure for concrete constructions comprising two flat strip like

members of equal width connected at their central portions and diverging therefrom towards their ends to form an X, and the 35 ends of said members being slit and bent in opposite directions to form a rectangular pocket each side of which is parallel to and in alignment with the side of a pocket formed in an adjacent end. 40

2. A device of the character described, comprising two strip-like members crossed at their central portions, the ends of said members being slit longitudinally, and the 45 portions of the same slit end being bent in different directions, one portion of a slit end being in alignment with a similar portion of one adjacent end, and the other portion of the first-named slit end being in alignment with a similar portion of the 50 other adjacent end.

3. A device of the character described, comprising two strip-like members crossed at their central portions and diverging toward their ends, the extremities of said 55 members being bent laterally relatively to the main direction of the respective members, the bent extremity of one member being in line with the bent extremity of the other member. 60

In testimony whereof I have signed this specification.

ROWLAND McWILLIAMS.
